UNITED STATES PATENT OFFICE

152,469

DESIGN FOR A JEWELRY SETTING

Merris Goodman, Indianapolis, Ind.

Application October 4, 1948, Serial No. 148,950

Term of patent 14 years

(Cl. D45—1)

To all whom it may concern:

Be it known that I, Morris Goodman, a citizen of the United States, residing at Indianapolis, in the county of Marion and State of Indiana, have invented a new, original, and ornamental Design for Jewelry Setting, of which the following is a specification, reference being had to the accompanying drawing, forming a part thereof.

Fig. 1 is a plan view of a jewelry setting, showing my new design;

Fig. 2 is a side view thereof; and

Fig. 3 is a section on line 3—3 thereof.

I claim:

The ornamental design for a jewelry setting, as shown.

MORRIS GOODMAN.
